UNITED STATES PATENT OFFICE.

FRANK ALSIP, OF CHICAGO, ILLINOIS.

KILN.

SPECIFICATION forming part of Letters Patent No. 679,817, dated August 6, 1901.

Application filed January 9, 1901. Serial No. 42,604. (No model.)

To all whom it may concern:

Be it known that I, FRANK ALSIP, a citizen of the United States, residing at Chicago, in the county of Cook and State of Illinois, have 5 invented certain new and useful Improvements in Kilns, of which the following is a specification.

My invention relates to that class of kilns used for burning bricks or tiles, and particularly to the variety commonly designated as "downdraft-kilns," all of which will more fully hereinafter appear.

The principal object of my invention is to provide a simple, economical, and efficient 15 fireproof suspensible kiln-cover and means for suspending and holding it suspended above the kiln, particularly while the material therein is being burned.

A further object is to provide means where- 20 by such kiln-cover may be readily placed in position section by section and any desired section removed or replaced without disturbing or removing any other section or portion of the kiln-cover.

25 A still further object is to provide means whereby any portion or section of the kiln-cover may be quickly and readily repaired by substituting a sound section or portion for that which is damaged or imperfect while the 30 contents of the kiln are being burned or subjected to heat, means for attaching metal supports operatively to the suspensible kiln-cover, so as to hold it in place while subjected to the heat from the kiln without the 35 metal being weakened or melted by such heat, and means for shielding the metal support from direct contact with the full force of the heat from the kiln.

Other objects of the invention will appear 40 from an examination of the drawings and the following description and claims.

The invention consists in the features, combinations, and details of construction herein- 45 after described and claimed.

The accompanying drawings show a brick- 50 kiln provided with my improved suspensible kiln-cover and the means for supporting the same, being a kiln of the ordinary and well-known type, but having the comparatively thin walls rendered available by my improve- 55 ments, in which—

Figure 1 is an upright transverse sectional

view of a brick-kiln of the ordinary down-draft type having comparatively thin walls and provided with my improved suspensible 55 kiln-cover and means for supporting the same; Fig. 2, an enlarged plan view of a portion of the cover, taken on line 2 of Fig. 1, showing a desirable shape and relative position of the slabs and slab-supporting blocks; Fig. 3, an 60 upright transverse sectional view showing a portion of a wall of the kiln and a portion of the kiln-cover and supports; and Fig. 4, an upright lateral sectional view of a portion of the kiln-cover and supports, taken on line 4 65 of Fig. 3 looking in the direction of the arrow.

In constructing a kiln in accordance with my improvements I build the walls *a* of the kiln in the ordinary and well-known manner, making them thinner than would be necessary 70 in connection with the arched cover commonly known and used. Though desirable, however, the thinness of the walls is not essential, and they may be made as thick as desired. These walls are provided at intervals along the sides of the kiln with flues *b*, of the ordinary and well-known type, extending therethrough and opening into the space *c* between the top course or layer of brick or other material to be burned in such kiln 80 and the under side of the suspensible cover *d*. Flues *e* are provided beneath the kiln at desired intervals leading from the inner space *f* of the kiln to the outer air. The bricks or other material to be burned are set in the 85 space *f* and slightly separated from each other to permit the draft to pass through the interstices between them. As will be seen from an inspection of the drawings, the current of hot air passes from the fire-boxes *a'* through 90 the flues *b*, the space *c*, the interstices between the bricks (not shown) in space *f*, and through flues *e* and stack or exhaust-fan (not shown) to the outer air, as indicated by the arrows. This exposes the under side of the 95 kiln-cover *d* to great heat.

It is desirable that the kiln-cover be suspended above the material to be burned in such manner as to withstand and confine the heat necessary for the proper burning of the 100 brick in the kiln and so that it can be readily placed in position or removed therefrom section by section. This enables the cover to be quickly and readily repaired while the

material in the kiln is being burned without seriously interfering with such process and without destroying or disturbing other portions of the cover. To accomplish this result, 5 I extend the side walls of the kiln upward beyond the top line of the bricks to be burned, as at *h*, so that the walls form a substantial support for the kiln-cover. Cross beams or girders *i* are provided, which extend from side 10 wall to side wall and rest thereon, and on these beams are extended, laterally of the kiln and at desired intervals, supports *j*, as shown in Figs. 2 and 3. In constructing these supports *i* and *j* I prefer to use steel or cast- 15 iron I-beams, as shown in the drawings. From the supports *j* are hung suspension- rods *k*, by means of which the roof is connected with and suspended from the supporting-beams *j*. The lower end of each of the 20 suspension-rods is provided with a pair of jaws *m*, which I prefer to make of one integral piece of spring metal, each jaw being perforated, so that the suspension-rod may be passed therethrough and support the same 25 by means of the head *n* on the rod. Suspensible blocks *o* are provided, having notches therein, into which the ends of the jaws are inserted in the manner shown in Figs. 3 and 4 to hold them in their suspended position. 30 These suspensible blocks are also provided with shoulders *q* and *r*, upon which are placed slabs *s*, which are held in position thereby and which, with the rods and means for connecting the blocks thereto, constitute 35 the suspended portion of the kiln-cover. The portion *t* of each of the suspensible blocks extends upward between the slabs a distance from the lower face of the blocks and slabs, so as to permit the metal supports to be attached thereto at a distance from the lower 40 heated portions of the blocks and prevent the metal jaws which hold the blocks from being weakened or melted by the heat from the kiln and also to hold the blocks and slabs in 45 their proper relative positions. In order that the suspensible blocks and slabs may withstand the high heat of the kiln, I make them preferably of fire-clay, pressed or molded into the desired size and shape. A sheet of 50 asbestos *X* may be laid over all the fire-brick slabs *s* to lessen the radiation and more thoroughly protect the suspension-rods *k*. Being necessarily exposed to the heat within the kiln and to atmospheric changes, these 55 suspensible blocks and slabs are subject to contraction and expansion caused by change of temperature. To prevent injury by such expansion and contraction, I arrange the slabs and blocks so that a small space *u* intervenes 60 between the upright portions thereof. This arrangement, as will be readily perceived, results in the metal supports being removed from the extreme heat of the kiln and shielded therefrom by the blocks and slabs, making a 65 comparatively light structure, which is both economical and efficient and provides for a light inclosing wall. It will be readily ap-

parent that in view of the comparative lightness and peculiar construction of this cover it can easily be mounted on wheels and the 70 wheels mounted upon tracks extending from one kiln to another and removed from one kiln to another by such means, either as a whole or in sections when desirable; but it is deemed unnecessary to show such wheels or 75 tracks, and the possibility of separating certain sections from others, and thus rendering them readily transportable, will readily appear from an inspection of the drawings. The principal advantages incident to the 80 use of my improvements are, first, simplicity, economy, and efficiency of construction and operation; second, the ready removability of the roof, enabling it to be used upon another kiln while the contents of the kiln already 85 burned are being removed or new material placed therein to be burned; third, the capability of being placed in position section by section, enabling the brick or other material already set to be protected thereby while 90 any desired space in the kiln remains uncovered and also enabling a damaged or imperfect section or portion to be quickly and readily replaced by a sound one while the contents of the kiln are being burned and the 95 cover exposed to great heat; fourth, the lightness of the cover; fifth, the lightness of the kiln-walls, and, sixth, the removal of the limitation of the width of the kiln, which limitation is inseparable from the use of an 100 arched cover of the ordinary type, these improvements rendering possible the practically unlimited size of the kiln as to width and length.

I claim—

1. In a kiln of the class described, a sectional kiln-cover formed of a plurality of suspensible blocks, a plurality of fireproof slabs resting upon the blocks, and means for suspending the blocks in position, substantially as described.
2. In a kiln of the class described, a sectional kiln-cover formed of a plurality of suspensible blocks provided with upwardly-projecting portions and laterally-extending portions forming flanges or shoulders, a plurality of slabs formed of fireproof material resting thereupon to provide in connection with the suspensible blocks a lower fireproof surface where it is exposed to the heat of the kiln, and means for holding the suspensible blocks by their upwardly-projecting portions, substantially as described.
3. In a kiln of the class described, the combination of a sectional kiln-cover, a series of main supporting-beams extending from side wall to side wall of the kiln and supported thereby, a plurality of secondary supports resting upon the main supporting-beams, and means for suspending the cover from the secondary supports, substantially as described.
4. In a kiln of the class described, the combination of a plurality of supporting-beams arranged above the kiln, upright supports

upon which the supporting-beams rest, a plurality of secondary supports extending laterally of the kiln and resting upon the main supporting-beams, a sectional kiln-cover formed of a plurality of suspensible blocks and a plurality of slabs resting thereon, and a series of rods supported by the secondary supports and provided with jaws which grasp the suspensible blocks and hold such blocks and slabs suspended above the space inclosed between the walls, substantially as described.

5. In a kiln, a plurality of suspensible supporting-blocks, a plurality of fireproof slabs arranged between the suspensible blocks and supported thereby, and means for suspending the blocks and slabs above the kiln-space, substantially as described.

10

15

6. In a kiln, a plurality of fireproof slabs, a plurality of suspensible blocks, each provided with an upwardly-extending portion 20 projecting between the slabs, and means for suspending the blocks and slabs above the kiln-space, substantially as described.

7. In a kiln, a plurality of suspensible fireproof supporting-blocks, a plurality of fireproof slabs arranged side by side and covering the area between the suspensible blocks and supported by such blocks, and means for suspending the blocks and slabs above the kiln-space, substantially as described.

FRANK ALSIP.
